INVENTOR
Rudolph Sattler
Clarence Perdew
ATTORNEY

UNITED STATES PATENT OFFICE.

RUDOLPH SATTLER, OF CINCINNATI, OHIO.

PLATE-PRINTING MACHINE.

Application filed August 19, 1922. Serial No. 582,932.

To all whom it may concern:

Be it known that I, RUDOLPH SATTLER, a citizen of the United States, residing at Cincinnati, in the county of Hamilton and State of Ohio, have invented certain new and useful Improvements in Plate-Printing Machines, of which the following is a specification.

My invention relates to printing from engraved plates, and more particularly to machines such as those disclosed and claimed in my patents, No. 1,447,433 issued March 6, 1923, No. 1,447,434 issued March 6, 1923, and No. 1,447,435 issued March 6, 1923, on which my present invention is an improvement. In many respects, the present machine is the same as the one specifically claimed in the past mentioned patent; and this patent will be referred to herein in connection with the description of several of the details, and also is referred to as to broader claims therein for several parts of the present machine. The object of the present invention is to further increase the ease and accuracy of operation, and make the machine more convenient and safe for the operator. Other objects will appear in the course of the ensuing description.

I attain these objects by the device illustrated, for example, in the accompanying drawings, in which—

Figure 1 is a plan view, certain parts being broken away to reveal underlying details;

Fig. 2 is a lengthwise section, partially on the vertical plane of the line 2—2 of Fig. 1, to show the bed-return mechanism, and partially on the vertical plane of the line 2'—2' of Fig. 1, to show the D-roller bearing mounting;

Fig. 3 is a rear elevation of the machine and parts of its support and side tables, parts of the covers being broken away and the return mechanism in raised position being indicated by dotted lines;

Fig. 4 is a partial lengthwise section on the vertical plane of the line 4—4 of Fig. 1, showing the meshing and locking mechanism;

Fig. 5 is a similar section on the vertical plane of the line 5—5 of Fig. 1, showing the guard mechanism, the relative position of the D-roller also being indicated, by dotted lines;

Fig. 6 is a partial side elevation showing

the D-roller holder and bed-holding dog; and

Fig. 7 is an enlarged vertical sectional detail of the clamp-screw and its nut and lock nut in relation to the arch-cap, part of which is shown.

The frame is like that of the second and third patents referred to, comprising a base 1, sides 2 and 3, and struts 4 connecting the sides. The bed 5 slides in guideways in the upper parts of the sides 2 and 3, rearwardly and forwardly, and is supported by rollers 6, 7 and 8, with straight lower faces 9 on these rollers. It differs from the one of the prior disclosure in having its lower side continuous throughout its major front part; and the pressure roller 10, mounted on eccentric adjustable bearings 11 as in the prior device, is continuous from end to end to afford a firmer support for this part of the bed.

Each frame side 2 or 3 has on its top rear pedestals 12 and front pedestals 13; the rear ones having ears 14, to which are pivoted the rear ends of substantially semi-circular arch-caps 15; having their front ends over the respective front pedestals 13, and recessed above to afford flat tops, from which openings extend down through the caps. To hold each cap down, a tension rod 16 is fixed in the respective pedestal 13, extending up through the arch-cap opening, and threaded in its upper end part. The cup-shaped nut 17 has its bottom threaded onto this rod and has its top open and loosely receiving the tubular lock-nut 18 threaded onto the rod, with radial opposite slots 19 in its top, and compressing a spring 20, coiled around the rod, against the bottom of the cup. A rod 21 through the top of the cup, engaging in the lock-nut slots 19, holds the parts in adjusted position and affords a finger-hold for screwing the device up or down on the rod 16.

On its interior under side, each arch-cap 15 has side flanges 22, and into the hollow of this under side, between these flanges, the ball-bearing 23 fits snugly, supported by a compression spring 24 set in a socket in the respective frame-side top between the pedestals 12 and 13. Screwing the nut or cup 17 up or down on the rod or screw 16, allows this bearing 23 to rise as pressed up by the spring 24, or depresses this bearing against the pressure of this spring, while maintain-

ing the bearing firm in its socket in the under side of the arch-cap. The spring 20 within the cup 17, more or less tightly binding the threads of the tubular lock-nut 18 against the threads of the screw 16, according to the up or down adjustment of this lock-nut while the bar 21 is removed, serves to prevent slippage of the main nut or cup 17 from its adjusted position on the screw 16, yet allows this nut 17 to be turned manually without any preliminary operation. The ball-bearings 23 support the D-roller 25, of segmental shape as in my previous disclosure, to rotate over the bed 5, by means of the transverse shaft 26 through the roller 25 and snugly fitting in the inner members of the ball-bearings.

As in the previous device, the mutilated gear 27 is fixed to the roller 25 and its shaft 26, next to the right-hand bearing (looking from the front); and a rack 28 is mounted along the right-hand side of the bed 5 to travel therewith, having teeth upward to mesh with the toothed part of the gear 27 at the proper time, and this rack can slide lengthwise by virtue of a spring 28' at its front end, as fully described in my prior patent last mentioned. The shaft 26 extends out at the left, with a spur-gear 29 clamped thereon, meshing with a similar gear 30, which in turn meshes with a spur-gear 31 twice its diameter; these gears being rotatably mounted on the frame side 2 and making up a train reaching from the D-roller down to the rear of the machine, as in the previous device. The large gear 31 carries the locking yoke 32 and the gear-sectors 33 adjacent the diametrically opposite ends of this yoke, as in that device.

40 The main shaft 34 reaches out to the left from the casing 35 and carries the rotor 36 at its outer end, between which and the casing 35 it has a bearing 37 extending through the frame side 2. This rotor 36 comprises 45 the hub 38 and the flange 39 on the outer end of this hub. A cover 40 surrounds the gears and this rotor. This mechanism is substantially the same as that in my previous disclosure, except that the brake therein shown is here omitted; and I have provided for insuring the correct timing of the mechanism, as will be described. Thus, as 50 as in the previous device, the rotor hub 38 has a slot carrying the segment-bar 41 projecting radially, with teeth on its end to mesh with either one of the gear-sectors 33; and the locking-segment 42 is fixed to the inner side of the flange 39 partly around the hub 38, to swing into either concave end 55 of the locking-yoke 32, having its advanced end rounded, but its opposite end being radial to the shaft 34. Near the rounded end of this segment 42, the timing pin 43 is fixed in the inner side of the flange 39, at 60 such a position that it will engage with the

outer straight edge 32' of the locking-yoke 32, coming up from below as the shaft 34 rotates over backward. This timing pin 43 thus is adapted to guide the corner or horn of the yoke 32 in between itself and the segment 42 to insure the correct positioning of this yoke and the segment 42 to each other as they are about to coact for stopping this mechanism and the D-roller 25 by the fitting of the convex segment 42 in the concave 75 locking-yoke end, as best seen in Fig. 4.

The mechanism within the casing 35 is the same as in my prior disclosure, comprising the clutch 44 which is allowed to mesh by depression of the starting-lever 45, at the front left side of the machine, to which the clutch is operatively connected by the starting-shaft 46 journaled along from front to rear inside the frame at the left, with an arm 47 projecting into the casing 35 for connection to the clutch-controlling bar or finger 48. Also, this mechanism comprises two sets of gears by which the shaft 34 may be driven at either one of two speeds from the worm 49, accordingly as these gears are 90 shifted by the shifter-shaft 50 extending out to the front of the machine. The details of the clutch 44 and this change-speed device being fully set forth in the third mentioned patent, further description thereof 95 herein is deemed unnecessary. However, I have provided a holdout device for the clutch 44, comprising a small lever 51 fulcrumed on the journal-stud of the front left-hand bed-supporting roller 6 between this 100 roller and the inside of the frame-side 2, with an upper arm 52 engaged by a pin 53 fixed in the adjacent edge of the bed 5 below the frame top, to force this arm 52 forward as the bed 5 returns to its forward 105 position, and with a lower arm 54 depending alongside the starting-shaft 46 at the left thereof. On this shaft 46 is fixed a block 55 with a flat left side having at its front end a shoulder 56. When the bed 5 travels 110 backward, carrying its pin 53 away from the upper arm 52, the lever 51 is swung by a spring 56', coiled around the fulcrum stud with one end engaging the lever and the other end engaging the frame side 2, so that 115 the lower arm 54 swings alongside the flat part of the block 55 until stopped by the shoulder 56. In this position, the lever arm 54 prevents depression of the starting-lever 45 and turning of the starting-shaft 46; and 120 it will have this position except when the bed 5 is at its forwardmost or stock-receiving position, when it is proper to depress the lever 45 and throw the clutch in for starting the bed backward. This provision 125 finds its utility in conjunction with an improvement which I have made in the driving and control of the bed 5, which now will be described.

The shaft 34, at the right-hand side of 130

the casing 35, carries the crank 57, similar to that of the prior device; but carrying a roller 58. The bed 5 has the depending ears 59 near its rear end, to which is connected 5 the link 60 also connected to the upper end part of the main lever 61 having its fulcrum 62 in the rear bottom part of the casing 35. These parts are similar to the prior device, except that the lever 61 has no forward 10 guide for coaction of the crank 57 therewith; merely having the rear guide 63 against which bears the roller 58 of the crank, so that the crank 57 drives the bed backward, but cannot cause its return forwardly. For effecting this return, a web 64 has its end fixed to the rear end of the bed 5 at the right, inside the frame, and passes 15 forwardly, downwardly and to the rear, around a small sheave 65 journaled on the same stud with the forward one 7 of the two rear bed-supporting rollers at that side, and then over another similar sheave 66 similarly journaled on the stud of the other one of these rollers, 8. From here the web 20 64 passes vertically downward along a guide 67 extending up from the rear end of the base 1 and has its lower end fixed in an eye on the upper end of a weight-rod 68 that passes down through and is guided by a 25 foot 69 on the lower end of this guide 67. The lower end of the rod 68 carries a weight 70, and has a spring 71 coiled around it above the weight 70 which is compressed between this weight and the guide-foot 69 as 30 the bed approaches its rearmost position. This spring 71 thus cushions, or brakes, the rear end of the bed travel, taking the place of the brake which I provided around the rotor hub 38 of the mechanism in my previous machine mentioned. The bed is 35 returned forward by gravity, acting on the weight 70; and it will be held by this weight, with the guide 63 of the main lever 61 held firmly against the crank roller 58. 40 This eliminates any irregularities or knocking due to wear or inaccurate fitting of a crank block between two lever guides, as in the prior device.

To cushion the front end of the bed travel, the plate 72 which is mounted across the rear end of the frame top, with its end parts forming clips to hold the bed 5 down in guides in the frame, as in the prior disclosure, has formed in its middle, on top thereof, a horizontal rearwardly opening dash-pot 73; and the rear end of the bed 5 has a rearwardly extended arm 74 with its rear end projecting upward and having fixed in it the plunger rod 75 carrying at 45 its front end the plunger 76 to enter the dash-pot 73 in the latter part of the forward travel. Near its front end the dash-pot 73 has a port 77 controlled by a small check-valve 78 which admits air more freely 50 than it allows the air to escape; thus avoid-

ing obstruction to rearward starting, but causing some compression of air as the plunger 76 enters at ending of the forward return stroke. However, the creation of some degree of vacuum inside the dash-pot 70 at starting backward is useful in preventing too sudden starting and jarring of the stock from its position; thus contributing to this result along with the lever and link arrangement as fully described and as claimed in 75 my third mentioned patent. To secure these results with this port and check-valve, the latter is made adjustable by means of the small tube 79 screwed into the port above the valve 78, which is in the form of a ball 80 pressed up against this tube by a small spring 80 resting on an annular shoulder in the lower end of the port 77. A lock-nut 81 holds the tube 79 in adjusted position.

As the bed is returned forward by gravity, it is possible to stop it manually, as by the operator leaning against it, before it reaches its correct extreme forward position; or to push it back from this position in the same manner, so far as the driving 90 mechanism including the main lever 61 is concerned. Should it be thus positioned, and then the clutch 44 thrown in, the machine would be operated out of time, with possible damage. Hence the small lever 51 95 preventing this unless the bed is fully forward, as previously described.

Also, it is desirable to prevent manual pushing of the bed 5 back from this position as just mentioned. Also, as the D-roller 100 completes its revolution under the action of the mechanism comprising the locking-yoke 32, and stops by the coaction of this yoke and the segment 42 as before mentioned, and as is fully set forth in my third mentioned patent, this D-roller 25 has a preponderance of weight leaning over backward, as clearly seen where the roller 25 is indicated by dotted lines in Fig. 5. The result is that, due to necessary back-lash in 110 the gearing of the mechanism mentioned, this roller drops slightly as the locking-yoke 32 and segment 42 complete their stopping coaction, and this produces a slight jar of the entire machine when started again and 115 picking up this roller 25 from this dropped-back position.

I provide for avoiding this back-drop of the D-roller, as well as guarding against untimely back-travel of the bed 5, in a single 120 device. At the right, the D-roller shaft 26 extends out past its bearing in the arch-cap 15, and a cam 82 is fixed to turn with this shaft. This cam 82 has a periphery that increases in radius from a point that lies substantially radially to the rear of the shaft 26 when the D-roller is stopped, as seen in the drawings, around to an abrupt drop 83 back to this point. Close to the greatest radius, a lug-plate is fixed to the inner side 125 130

of the cam, projecting out past the cam periphery with its periphery of increasing radially outward distance from a point about 90° in advance of the drop 83 to terminate abruptly somewhat in advance of the drop 83, with a concave end 84.

The lever 85 is fulcrumed on the frame side below and to the rear of the shaft 26 and extends up and leans forwardly with a roller 86 bearing on the cam periphery and fitting snugly in the concave rear end 84 of the lug-plate on the cam, to hold the D-roller in its stopped position without back-drop and ready to start over forwardly without shock as the segment-bar 41 meshes with the gear sector 33 when the clutch 44 is thrown in. A spring 87, at the fulcrum, with ends, respectively, on the lever 85 and on the frame, forces this lever forward against the cam 82 as just described.

This lever 85 carries, inside the frame, over the edge part of the bed 5, a housing 88, open at its bottom and covering a dog 89 fulcrumed on the same pin with the lever 85 and held down by a spring 90 between its top and a screw 91 in the housing top, by which the spring may be adjusted. The edge part of the bed 5 has on top a lug 92 with gently inclined front and undercut rear end; and the dog 89 has a nose 93 on its rear end with front sloped up rearwardly to wedge down under the rear end of the lug 92 if the bed starts backward. As the D-roller starts over forward, the roller 86 drops forward at the drop 83, and with it the lever 85, raising the housing 88. The dog 89 has its front part engaged with the housing, and is raised therewith, out of the path of the bed lug 92. The bed 5, owing to the lever-and-link driving means, acted upon by the crank, starts very slowly, but the D-roller starts more rapidly, from its directly engaged connection through sector 33 and bar 41; so that the latter has ample time to remove the dog 89, which does not bind the bed lug 92 closely, but permits a negligible amount of backward movement of the bed when in the path of the lug. When the bed 5 returns forwardly, the dog 89 rides up on the inclined front of the lug 92, spring 90 yielding, and then is forced down behind it by the spring; the D-roller having long since come around and stopped with the arm or lever 85 held back with the dog down in the path of the lug.

Between the left end of the D-roller and the adjacent arch cap 15, another cam 94 is mounted to turn with the shaft 26, for operating a guard comprising a bar 95 which extends across the top of the bed from the lower end of a lever 96 having a fulcrum 97 on top of the arch-cap 15; this lever being curved to reach down around the front of the shaft 26 and hold the guard bar 95 under the D-roller reduced portion.

when the D-roller is stopped as seen in the drawings. This lever has a roller 98 bearing on the periphery of the cam 94. About half of this periphery is concentric with the shaft 26, but its other half recedes rapidly radially inwardly, from both ends to its middle and holds the roller 98 for holding the bar 95 down in the described position. As the D-roller starts over forward, the roller 98 rides out onto the higher parts, 75 swinging the lever 96 upward and forward, and the bar 95 therewith, out of the path of the descending larger operating part of the D-roller, and forcing the hand of the operator away therefrom if not removed in 80 time by the operator.

In my present machine I have made the bed much wider in proportion to the maximum dimension of plate to be operated upon, which, in any plate printing-machine 85 is much smaller than the bed surface. This is to afford the operator ample room for operating at the rapid rate permitted by power operation. The clip bar 99 which holds the bed down at the left is carried forward past the front end of the frame, covering the bed guideways at extreme forward position, as also is the cover 100 over the rack 28 at the right. This prevents escape of the lubricant of these operating parts, or 90 contact therewith, avoiding contamination of the ink and soiling of the stock. A tray 101 is mounted on the front end of the bed for further convenience of the operator.

As suggested in the patent last mentioned, 100 instead of having the motor directly connected with the shaft of the worm 49 of the driving means, the motor 102 is mounted on a shelf 103 supported on the legs 104 of the machine, partly shown in Fig. 3. The 105 motor shaft carries a fly-wheel 105 and a pulley 106, and a belt 107 passes from this pulley up through an opening 108 in the base 1, to a pulley 109 on the shaft 110 of the worm 49.

The forward part of the shaft 110 has a trunnioned bearing 111 on pedestals of the base 1, permitting it to adjust to varying strains or inaccuracies of alinement in assemblage. The front end of this bearing 111, which extends alongside the support 112 of the heater-lamp 113, is recessed around the shaft 110, and this shaft has a key 114 that can be engaged by a suitable implement, such as a crank, inserted in the 115 recess of the bearing. This permits the machine to be operated manually in the course of setting it up and adjusting its various parts to operate in time with each other as before described.

Due to the combination of the crank-roller and weight for driving the bed, and the D-roller holder to eliminate shock in starting the D-roller, as well as the more 120 certainly correct relation of the locking 125

elements 32 and 42, insured by the timing pin 43, the operation of the machine is extremely smooth and regular. These parts contribute to this in conjunction with the 5 crank, lever and link arrangement, for driving the bed, and the rack and segment-gear for driving the D-roller from the bed, which are the special subject matter of the third mentioned patent. No special holders 10 for the plate A (Fig. 1) to prevent its slippage, are needed, as were provided in said prior device.

The plate may be secured to the bed by some adhesive, such as soap, for instance. Placed on the bed, face up, the plate is inked in the usual manner. The D-roller carries a suitable blanket, clamped thereon as well known in the art; and as fully described in my prior patent, the rack 20 and segment are so related that the bed and D-roller will have the same surface speed when the blanket reaches the stock, which has been placed face down on the plate. The machine is started by depressing lever 45, which is permitted since bed 5 has pushed small lever 51 away from block 55. This allows clutch 44 to mesh, the driving means starting the crank 57, which starts the bed 5 very slowly backward against whatever pressure might result from imperfect inflow of air to dashpot 73 as before mentioned. Segment-bar 41, through the gearing, starts D-roller 25 at the same time, but more rapidly, removing 35 dog 89 from path of lug 92, so that bed 5 is free to travel in its printing movement.

The segment gear 27 now meshes with the rack 28 while segment-bar 41 unmashes from gear sector 33; the bed now controlling 40 the speed of the D-roller, since the D-roller is driven by the bed. This backward travel is raising weight 70, and at ending will be cushioned by compression of spring 71. This weight holds the lever 61 forward 45 against the crank roller 58 so that there is no jar due to wear in these parts. In return movement, the crank roller 58 is traveling near the fulcrum of the lever 61, and the compressed spring 71, together with 50 the weight, starts the bed forward, on its return, quickly.

As the bed reaches the rear end of stroke, rack 28 releases gear 27, after having raised D-roller 25 away from bed 5, and segment 55 42 and yoke 32 assume the duty of holding the D-roller up after completing the slight remainder of its rotation. It is in this transfer of the D-roller control from bed 5 to locking elements 42 and 32 that the 60 timing pin 43 serves its purpose; compelling these two parts 42 and 32 to fit together as designed to fit, whatever looseness there may be in the machine parts, with the radial end of the segment 42 in the 65 deepest part of the concavity of the end of

the yoke 32. It is to insure further that the D-roller will have its operative connection immediately engageable, at the bar 41 and sector 33, without impact, that the holding means comprising the roller 86 engages the end 84 on the cam of the D-roller. At the end of the forward return movement of the bed, the dash-pot 73 cushions the travel, which again is very slow, due to the crank, lever and link drive; and 75 the clutch 44 automatically unmashes, upon which the machine is ready for a recurrent operation.

The various details have been somewhat specifically described, to make clear the construction and use of my invention, as is required, but I do not wish to be understood as being limited to such precise showing and description, but having thus fully described my invention, what I claim as 80 new and desire to secure by Letters Patent is:—

1. In a machine of the character described, in combination with a bed having a printing movement and a return movement, pressing means, and mechanism causing said pressing means to press stock on said bed during part of said printing movement, a crank, engaging means whereby said crank drives said bed in printing movement 90 but not in return movement, and means causing said return movement.

2. In a machine of the character described, in combination with a bed having a printing movement and a return movement, pressing means, and mechanism causing said pressing means to press stock on said bed during part of said printing movement, a crank, a lever connected to said bed having a bearing whereby said crank drives 100 said bed in printing movement but not in return movement, and means causing said return movement.

3. In a machine of the character described, in combination with a bed having a printing movement and a return movement, pressing means, and mechanism causing said pressing means to press stock on said bed during part of said printing movement, a crank, a lever connected to said bed having an elongated bearing, and a roller on said crank against said bearing, whereby said crank drives said bed in printing movement but not in return movement, and means causing said return movement.

4. In a machine of the character described, in combination with a bed having a printing movement and a return movement, pressing means, and mechanism causing said pressing means to press stock on said bed during part of said printing movement, a crank, engaging means whereby said crank drives said bed in printing movement 125 but not in return movement, a spring resisting said bed near the end of printing 130

movement, and means causing said return movement.

5. In a machine of the character described, in combination with a bed having a printing movement and a return movement, pressing means, and mechanism causing said pressing means to press stock on said bed during part of said printing movement, a crank, engaging means whereby said crank drives said bed in printing movement but not in return movement, a dash-pot resisting said bed near the end of return movement, and means for causing said return movement.

15. 6. In a machine of the character described, in combination with a bed having a printing movement and a return movement, pressing means, and mechanism causing said pressing means to press stock on said bed during part of said printing movement, a crank, engaging means whereby said crank drives said bed in printing movement but not in return movement, a spring resisting said bed near the end of printing movement, a dash-pot resisting said bed near the end of return movement, and means for causing said return movement.

7. In a machine of the character described, in combination with a bed having a printing movement and a return movement, movable pressing means, driving means, an engageable operative connection permitting said driving means to have action causing movement of said pressing means uncontrolled by the speed of said bed and then disengaging to cease said action, and mechanism whereby said bed causes movement of said pressing means to press stock on said bed during part of said printing movement after said action is ceased, finally withdrawing said pressing means from said bed, a crank turned by said driving means, engaging means whereby said crank drives said bed in printing movement but not in return movement, means for causing said return movement, a dog coming into retentive relation to said bed, against untimely printing movement, near the end of return movement, and means whereby said operative connection removes said dog from said relation upon recurrent operation.

8. In a machine of the character described, in combination with a bed having a printing movement and a return movement, pressing means, and mechanism causing said pressing means to press stock on said bed during part of said printing movement, a crank, engaging means whereby said crank drives said bed in printing movement but not in return movement, means for causing said return movement, a clutch controlling operation of said crank, an element holding said clutch to prevent said operation, and means whereby said bed actuates

said element at the end of return movement, to release said clutch.

9. In a machine of the character described, in combination with a bed having a printing movement and a return movement, movable pressing means, driving means, an engageable operative connection permitting said driving means to have action causing movement of said pressing means uncontrolled by the speed of said bed and then disengaging to cease said action, and mechanism whereby said bed causes movement of said pressing means to press stock on said bed during part of said printing movement after said action is ceased, finally withdrawing said pressing means from said bed, a crank turned by said driving means, engaging means whereby said crank drives said bed in printing movement but not in return movement, means to cause said return movement, a clutch controlling operation of said driving means, an element holding said clutch to prevent said operation, means whereby said bed actuates said element at the end of return movement, to release said clutch, a dog coming into retentive relation to said bed, against untimely printing movement, near the end of return movement, and means whereby said operative connection removes said dog from said relation upon recurrent operation.

10. In a machine of the character described, in combination with a bed having a printing movement and a return movement, movable pressing means, driving means, an engageable operative connection permitting said driving means to have action causing movement of said pressing means uncontrolled by the speed of said bed and then disengaging to cease said action, and mechanism whereby said bed causes movement of said pressing means to press stock on said bed during part of said printing movement after said action is ceased, finally withdrawing said pressing means from said bed, holding means engaging directly with said pressing means to hold it away from said bed independently of action of said operative connection, and means to reciprocate said bed.

11. In a machine of the character described, in combination with a bed having a printing movement and a return movement, movable pressing means, driving means, an engageable operative connection permitting said driving means to have action causing movement of said pressing means uncontrolled by the speed of said bed and then disengaging to cease said action, and mechanism whereby said bed causes movement of said pressing means to press stock on said bed during part of said printing movement after said action is ceased, finally withdrawing said pressing means from said bed, a timing element con-

- trolling reengagement of said operative connection for recurrent operation of said pressing means, and means to reciprocate said bed.
12. In a machine of the character described, in combination with a bed having a printing movement and a return movement, movable pressing means, driving means, an engageable operative connection permitting said driving means to have action causing movement of said pressing means uncontrollable by the speed of said bed and then disengaging to cease said action, and mechanism whereby said bed causes movement of said pressing means to press stock on said bed during part of said printing movement after said action is ceased, finally withdrawing said pressing means from said bed, holding means engaging directly with said pressing means to hold it away from said bed independently of action of said operative connection, a crank turned by said driving means, engaging means whereby said crank drives said bed in printing movement but not in return movement, means to cause said return movement, and a dog coming into retentive relation to said bed, against untimely printing movement, near the end of return movement, mounted on said holding means, said pressing means having a part with a recess receiving said holding means early in a recurring operation, whereby said holding means removes said dog from said relation.
13. In a machine of the character described, in combination with a bed having a printing movement and a return movement, movable pressing means, driving means, an engageable operative connection permitting said driving means to have action causing movement of said pressing means uncontrollable by the speed of said bed and then disengaging to cease said action, and mechanism whereby said bed causes movement of said pressing means to press stock on said bed during part of said printing movement after said action is ceased, finally withdrawing said pressing means from said bed, a high-speed power device, gearing of high ratio whereby said device operates said driving means at low speed, a crank turned by said driving means, engaging means whereby said crank drives said bed in printing movement but not in return movement, means to cause said return movement, and means for attachment of an implement to said power device for operating said driving means manually in adjusting the relation of said bed, pressing means, driving means and operative connection to each other.
14. In a machine of the character described, in combination with a bed having a printing movement and a return movement, movable pressing means, driving means, an engageable operative connection permitting said driving means to have action causing movement of said pressing means uncontrollable by the speed of said bed and then disengaging to cease said action, and mechanism whereby said bed causes movement of said pressing means to press stock on said bed during part of said printing movement after said action is ceased, finally withdrawing said pressing means from said bed, holding

means engaging directly with said pressing means to hold it away from said bed independently of action of said operative connection, a crank turned by said driving means, engaging means whereby said crank drives said bed in printing movement but not in return movement, means to cause said return movement, and a dog coming into retentive relation to said bed, against untimely printing movement, near the end of return movement, mounted on said holding means, said pressing means having a part with a recess receiving said holding means early in a recurring operation, whereby said holding means removes said dog from said relation.

15. In a machine of the character described, in combination with a bed having a printing movement and a return movement, pressing means, and mechanism causing said pressing means to press stock on said bed during part of said printing movement, a crank, engaging means whereby said crank drives said bed in printing movement but not in return movement, a weight to cause said return movement, and a spring compressed by said weight, resisting said bed near the end of printing movement.

16. In a machine of the character described, in combination with a bed having a printing movement and a return movement, rollers on which said bed travels, pressing means, and mechanism causing said pressing means to press stock on said bed during part of said printing movement; a crank, engaging means whereby said crank drives said bed in printing movement but not in return movement, a sheave coaxial with one of said rollers, a web connected to said bed and running around said sheave, and a weight hung on said web to cause said return movement.

17. In a machine of the character described, in combination with a bed having a printing movement and a return movement, pressing means, mechanism causing said pressing means to press stock on said bed during part of said printing movement, finally withdrawing said pressing means from said bed, a sheave, a web connected to said bed and running around said sheave, a rod connected to said web, a guide for said rod, a weight on said rod to cause said return movement, and a spring coiled around said rod and compressed between said weight and said guide, resisting said bed, near the end of printing movement.

18. In a machine of the character described, in combination with a bed having a printing movement and a return movement, pressing means, and mechanism causing said pressing means to press stock on said bed during part of said printing movement, finally withdrawing said pressing means from said bed, means to reciprocate

said bed; a guard element having a position across said bed between said bed and said pressing means when said pressing means is withdrawn from said bed, and an operative 5 connection whereby said mechanism moves said guard from said position in direction opposite to said printing movement as said pressing means approaches said bed in the beginning of pressing movement.

10 19. In a machine of the character described, in combination with a bed having a printing movement and a return movement, segmental rotary pressing means, mechanism causing rotation of said pressing

15 means to press stock on said bed during part of said printing movement, finally withdrawing said pressing means from said bed, means to reciprocate said bed, a cam coaxial with said pressing means, a lever

20 having a part engaging said cam, and a guard element mounted on said lever and having a position across said bed between said bed and said pressing means when said pressing means is withdrawn from said bed,

25 said cam having its periphery of increased radius whereby it swings said lever and moves said guard element from said position in direction opposite to said printing movement as said pressing means approaches said bed in the beginning of pressing movement.

30 20. In a machine of the character described, in combination with a bed having a printing movement and a return movement, frame elements at opposite sides of

35 said bed, rotary pressing means, and means for reciprocating said bed, arch elements fulcrumed on the respective frame elements, each having a recessed lower side, bearings

40 for said pressing means, springs holding said bearings up against said recessed lower sides of the respective arch elements, upright threaded tension elements on the respective frame elements, cup-shaped nuts on these tension elements, holding the respective arch elements down against the bearings,

45 tubular lock-nuts threaded on the upper parts of said tension elements and fitting loosely inside of said cups, members extending across said nuts holding said

50 lock-nuts from rotation, and springs between said lock-nuts and the bottoms of said cup-shaped nuts, surrounding said tension elements.

55 21. In a machine of the character described, a rectilinearly reciprocating bed, segmental rotary pressing means to press stock on said bed during reciprocation of said bed in one direction and to withdraw from said bed during reciprocation in re-

60 turn direction, mechanism having an operation to cause said reciprocation of said bed, a segment gear on said pressing means, a rack on said bed initially removed therewith from said segment gear, an operative connection from said mechanism to said press-

ing means comprising a pair of rotary meshing means and a pair of rotary locking means, said locking means locking for holding said pressing means away from said bed while said bed reciprocates in the return 70 direction, a cam rotating directly with said pressing means, having a periphery of radius increasing to an abrupt concave end, and an element fulcrumed on said machine with a part against said periphery to enter 75 the concavity of said end as said locking means locks, to hold said pressing means away from said bed independently of said locking means.

80 22. In a machine of the character described, a rectilinearly reciprocating bed, segmental rotary pressing means to press stock on said bed during reciprocation of said bed in one direction and to withdraw therefrom during reciprocation in return di-

85 rectation, mechanism having an operation to reciprocate said bed in the one direction but not in the return direction, means to cause said reciprocation in return direction, a seg-

90 ment gear on said pressing means, a rack on said bed initially removed therewith from said segment gear, an operative connection from said mechanism to said pressing means comprising a pair of rotary meshing means and a pair of rotary locking means, said

95 locking means locking for holding said pressing means away from said bed while said bed reciprocates in the return direction, a cam rotating directly with said press-

100 ing means, having a periphery of radius increasing to an abrupt concave end, an element fulcrumed on said machine with a part against said periphery to enter the concavity of said end as said locking means locks, to hold said pressing means away from said bed independently of said locking means, a dog

105 pivoted adjacent to said fulcrumed element, a projection on this element, a spring be-

110 tween said projection and said dog, and means on said bed engaged by said dog to prevent untimely movement of said bed in printing direction, said cam having a fol-

115 lowing recess receiving said part of said fulcrumed element to permit said dog to leave the path of said means on said bed, early in the operation of said pressing means.

23. In a machine of the character described, in combination with a bed having a printing movement and a return movement, movable pressing means, driving means, engageable operative connecting means permitting said driving means to have an action

120 causing movement of said pressing means uncontrolled by the speed of said bed and then disengaging to cease said action, and mechanism whereby said bed causes move-

125 ment of said pressing means to press stock on said bed during a part of said printing movement after said action is ceased, finally withdrawing said pressing means from said

bed, a high-speed power device, gearing of high ratio whereby said device operates said driving means at low speed, a crank turned by said driving means, engaging means whereby said crank drives said bed in printing movement but not in return movement, means to cause said return movement, a spring resisting said bed near the end of printing movement, a dash-pot resisting said bed near the end of return movement, a timing element controlling reengagement of said operative connection for recurrent operation of said pressing means, holding means engaging directly with said pressing means 15 to hold it away from said bed independently of action of said operative connection, a dog coming into retentive relation to said bed, against untimely printing movement, near the end of return movement, means whereby 20 said operative connection removes said dog from said relation upon recurrent operation, a clutch controlling operation of said driving means by said power device, an element holding said clutch to prevent said 25 operation, means whereby said bed actuates said element at the end of return movement, to release said clutch, and means for attachment of an implement to said power device for operating said driving means manually 30 in adjusting the relation of said bed, pressing means, driving means and operative connection to each other.

24. In a machine of the character described, a rectilinearly reciprocating bed, segmental rotary pressing means to press stock on said bed during reciprocation of said bed in one direction and to withdraw therefrom during reciprocation in return direction, mechanism having an operation to 35 reciprocate said bed, a segment gear on said pressing means, a rack on said bed initially removed therewith from said segment gear, an operative connection from said mechanism to said pressing means comprising a 40 pair of rotary meshing means and a pair of rotary locking means, one locking means ex-

tending partly around the other with a horn at its side first approached by said other, and a timing pin carried around with this other locking means, near the advanced end 50 thereof, engaging with the horn of said one locking means and guiding the one locking means into correct relation with the other.

25. In a machine of the character described, in combination with a movable bed and pressing means coacting therewith, driving means for said bed and said pressing means, and a frame for said bed, pressing means and driving means, comprising a base, a support for said frame, a motor 55 mounted on said support below said base, a pulley rotated by said motor, gearing of high ratio operatively connected to said driving means, comprising a shaft above said base, a pulley on this shaft, and a belt passing 60 through said base from the first mentioned to the second mentioned pulley, a trunnioned bearing for said shaft, on said base, permitting said shaft to adjust to varying strains 65 and to inaccuracies of alinement in assemblage of said machine.

26. In a machine of the character described, in combination with a movable bed and pressing means coacting therewith, driving means for said bed and said pressing 75 means, and a frame for said bed, pressing means and driving means, comprising a base, a support for said frame, a motor mounted on said support below said base, a pulley rotated by said motor, gearing of high ratio 80 operatively connected to said driving means, comprising a shaft above said base, a pulley on this shaft, and a belt passing through said base from the first mentioned to the second mentioned pulley, a trunnioned bearing for said shaft, on said base, having a recess in one end around said shaft, and means on said shaft for attachment of an implement inserted in said recess, for operating said driving means manually. 85

RUDOLPH SATTLER.
